UNITED STATES PATENT OFFICE.

JAMES M. McCLELLON, OF EVERETT, MASSACHUSETTS.

FIRE-BOX FOR BOILERS.

1,072,865.

Specification of Letters Patent. Patented Sept. 9, 1913.

Application filed June 7, 1909. Serial No. 500,562.

To all whom it may concern:

Be it known that I, JAMES M. McCLELLON, a citizen of the United States, and a resident of Everett, in the county of Middlesex and 5 Commonwealth of Massachusetts, have invented an Improvement in Fire-Boxes for Boilers, of which the following description, in connection with the accompanying drawings, is a specification, like letters on the 10 drawings representing like parts.

My invention relates to the structure of boiler fire-boxes and more particularly to fire-boxes for boilers of the locomotive type.

The character of my invention may be 15 best understood by reference to the following description of an illustrative embodiment thereof shown in the accompanying drawing, wherein:

Figure 1 is a transverse vertical section 20 through a boiler fire-box embodying my invention; Fig. 2 is a plan view of a portion of the boiler and fire-box shown in Fig. 1; Fig. 3 is an enlarged sectional detail of parts shown in Fig. 1; Fig. 4 is a view of 25 Fig. 3 looking toward the right; Fig. 5 is a horizontal section taken on line 5—5 of Fig. 3; and Fig. 6 is a detail hereinafter referred to.

The illustrative fire-box herein embodying my invention is shown in connection with a boiler of the locomotive type. This boiler comprises (see Fig. 1) a shell 1 provided with the usual longitudinal fire tubes 3 communicating with the fire-box. The side walls 35 of the latter (see Fig. 5) are each made of a row of connected, vertical, sectional compartments 5 constituting water legs through which the water from the shell may circulate as more fully hereinafter described. The 40 inner shell formed by said compartments consists of a plurality of channel bars 7, having long flanges 9 extending outwardly from the fire-box, said bars 7 alternating with channel bars 11 having short flanges which 45 are riveted to said long flanges. The outer shell formed by said compartments consists of channel bars 13 interposed between and riveted to the outer end portions of the outwardly extending long flanges 9 of said bars 50 7, said long flanges constituting stay plates for said shells. To permit the free circula-

tion of water from one compartment to another, the flanges 9 connecting the outer and inner surfaces may be provided with spaced openings 15 (see Figs. 1 and 3). 55

It will be apparent that a fire-box side built of compartments of flanged sections as described provides a wall or water leg of great strength and one in which the rivets for securing said flanges together are either 60 contained within said sections or are on the exterior of the wall and thus are isolated and protected from the fire in the fire-box thereby reducing liability of rupture or explosion to a minimum. Furthermore, by 65 this sectional construction any section or compartment may be readily removed for replacement or repair without disturbing the other sections. Also a side wall stayed as described need not be necessarily positioned 70 in a vertical position since its strength is sufficient to permit it to assume various positions to conform to the arrangement and size of the fire-box and other parts as desired. 75

I will now describe a mud chamber through which water may be supplied to the side wall communicating compartments. The lower ends of the latter are not set into a separate mud-drum or header but the channel stay flanges referred to are cut away or have portions removed at their lower ends as at 17 between the outer and inner surfaces of the walls to form a continuous chamber 19 contained within and extended throughout the length of said walls. The outer side of this mud chamber is formed by the lower back portions 21 of the outer channel bars 13 and the inner side is formed by the lower back portions 23 of the inner channel bars 9 80 and 11. The bottom of the mud chamber is formed by a mud ring 25 interposed between the end portions 21 and 23 which are flattened to conform to the flat sides of said mud ring and are secured to the latter by 85 rows of long bolts 26 extending therethrough. 90

To prevent leakage between the adjacent edges of the lower inner back portions 23 of the compartments such as might occur 100 because of the cutting away of the legs or flanges of the channels, the round backs of

the inner bars may be flattened as at 27 (Figs. 3, 4 and 5) and their edges welded together. To the flat surface thus formed is secured a reinforcing strip 29 extending the length of the wall and connecting said sections. This strip is of sufficient width to extend above the top of the opening formed by the cutting away of the flanges of the channel bars and is firmly secured to the 5 back portions 23 by rows of rivets 31 above and below the level of the lower ends of said flanges and is further secured by the long bolts 26 referred to. Since the upper edge of said strip is readily accessible its joint 10 may be calked if desired to contribute to the tightness of the seams between said channel backs 23.

By cutting away the lower ends of the flanges of the channels as described, is provided a simple, compact mud chamber which is contained within the side walls of the fire-box. By the use of the strip 29 extending the entire length of each side of the fire-box the inner wall of the mud chamber 20 is reinforced and strengthened, the compartments are connected at their bases and the joints between the backs of the lower ends of the channels are completely covered and protected and leakage is prevented. 25 Since the mud chamber is below the level of the fire-grate, none of the rivets connecting said strip 29 to the backs of the channels are exposed to the fire. The flanges of the lower outer channel back portions 21 and the vertical flange strips 24 therebetween may be 30 welded together further to prevent any possibility of leakage.

The front and rear ends of the fire-box are made of the usual spaced stayed sheets, 40 the rear sheet 33 only being shown herein. The mud chamber of the water legs may communicate at the ends of said legs with the spaces between the separated front sheets and rear sheets referred to thereby forming 45 a continuous mud chamber through which water may be supplied to all of the sides of said fire-box as desired.

The top of the fire-box (Figs. 1 and 2) is made of a plurality of cylindrical drums 50 35 extending longitudinally of the boiler and riveted to the rear fire-box sheet and similarly may be riveted to the front sheet (not shown). By the use of cylindrical drums to form the top of the fire-box stay 55 bolts are eliminated and there are no riveted seams exposed to the fire. The drums because of their equal length and cylindrical shape expand equally and being of small diameter will withstand a greater pressure 60 than the barrel of the boiler. Furthermore, there is no danger of overheating as long as any water remains in the drums, since the water gravitates toward the center of the lower curved sides of said drums and covers 65 that part of the drum surface which re-

ceives the greatest heat, whereas by the use of an arched fire-box crown sheet the water in lowering is pocketed at the sides of the arch, the top of the latter receiving the greatest heat being the first part to become dry and exposed, thereby greatly shortening the life of the fire-box top. These top drums are lighter and more durable than the crown sheet hitherto used and also being independently supported any one of said drums may be readily removed without disturbing the others. 70 75

The upper ends of the side wall sectional compartments are riveted and nipped to the outer top drums and to avoid disturbing the truly cylindrical sections of the latter the backs of the sections 5 are deformed or flattened as at 37 to conform to the contour of the drum surfaces at their points of attachment as well shown in Fig. 1. The 80 open upper ends of the vertical compartments are closed by suitable heads comprising cut-shaped sections 39 (see Figs. 1, 2 and 6) set therein and having upwardly extending sides or flanges 41 adapted to be 85 shaped to conform to the contour of the interior of said compartments and may be riveted thereto as desired. The drums 35 between the outer top drums may be covered by a suitable finishing sheet 43 bolted 90 to the top surfaces of the outer drums as shown in Figs. 1 and 2. The boiler also 95 may be provided with the usual steam dome 45 and superheater 47.

It will be observed that by connecting the 100 side top drums with a wall consisting of sectional compartments is provided a fire-box structure which is not only of great strength and elasticity with no stay bolts or rivets exposed to the fire, but also every 105 part is readily accessible for repair or replacement without disturbing other parts. For example, if access is desired to any portion of the union of said side drums with the compartments of the walls connected 110 therewith, any of the outer and readily accessible channels 13 may be removed, thereby exposing the interior of one of said compartments, its inner channel and the connections of the latter to the drum without 115 the necessity of removing the entire compartment, as would be necessary if the latter were of integral instead of flanged sectional construction. Furthermore, it will be apparent that the inner channels by virtue of 120 their contact with the fire will wear out and need to be replaced before the outer channels. By the sectional construction of the compartments new inner channels may be substituted and the outer channels retained 125 without the necessity of discarding the entire compartment, thereby making possible a great saving in material.

It will be understood that my invention is not limited to the particular embodiment 130

shown herein, but that various modifications may be made without departing from the spirit and scope of my invention.

Claims:

5. 1. In a fire-box the combination of a wall comprising flanged sections, the flanges whereof at their lower ends have portions removed, a connecting plate crossing the lower ends of said sections and secured to the unflanged faces thereof, and a mud-ring to which the lower edge of said plate is secured. 70
10. 2. In a fire-box the combination of outer and inner wall portions comprising outer and inner connected flanged sections, the flanges of the inner sections at their lower ends having portions removed, a connecting plate crossing the lower ends of said inner sections and secured to the unflanged faces thereof, and a mud-ring secured to and between said plate and the lower ends of said outer sections. 75
15. 3. In a fire-box the combination of a wall comprising flanged sections extending transversely to the length of the fire-box, the flanges whereof at their lower ends have portions removed, a connecting plate crossing the lower ends of said sections and secured to the unflanged faces thereof, and a mud-ring to which the lower edge of said plate is secured. 80
20. 4. In a fire-box the combination of a wall comprising a plurality of communicating compartments formed of flanged sections, the flanges whereof at their lower ends have portions removed, a connecting plate crossing the lower ends of said sections and secured to the unflanged faces thereof, and a mud-ring to which said faces and the lower edge of said plate are secured. 85
25. 5. In a fire-box the combination of a wall comprising a row of sectional connected compartments, the connecting portions whereof at their lower ends have portions removed, a connecting plate crossing the lower ends of said compartments and secured to the portions of the latter adjacent said removed portions, and a mud-ring to which the said plate is also secured. 90
30. 6. In a fire-box the combination of a wall comprising flanged sections, the flanges whereof at their lower ends have portions removed, the unflanged faces of said sections being flattened, a connecting plate crossing said faces and secured thereto, and a mud-ring to which said plate is secured. 95
35. 7. A boiler fire-box comprising, in combination, a wall comprising flanged sections, the flanges whereof at their lower ends have portions removed leaving unflanged faces having abutting edges, a connecting plate crossing the lower ends of said sections and secured to said faces, and a mud-ring secured to said plate. 100
40. 8. A boiler fire-box comprising, in combination, a top consisting of a plurality of drums, and side walls each comprising flanged sections secured to said drums, the flanges whereof at their lower ends have portions removed, a connecting plate crossing the lower ends of said sections and secured to the unflanged faces thereof, and a mud-ring to which the lower edge of said plate is secured. 105
45. 9. A boiler fire-box comprising, in combination, a wall consisting of a plurality of sections having closing cups at their upper ends and communicating at their lower ends to form a mud-chamber and a reinforcing strip for the latter. 110
50. 10. A boiler fire-box comprising, in combination, a wall consisting of a plurality of communicating sectional compartments having closing cups at their upper ends and having portions cut away from their lower ends to form a mud-chamber extended throughout the length of said wall and a reinforcing plate for said ring. 115
55. 11. In a fire-box, the combination of a closed crown comprising a plurality of drums, with side walls, each comprising a series of outer and inner flanged sections secured together and having provision permitting communication between the compartments formed by said sections, said sections being secured to said drums, and means permitting communication between said compartments and drums. 120
60. 12. In a boiler fire-box the combination of a plurality of drums forming the top of the fire-box, side walls each comprising a plurality of sectional compartments, the latter being riveted and nipped to some of said drums. 125
65. 13. In a boiler fire-box the combination of side walls, each comprising a plurality of sectional compartments, cup-shaped sections closing the tops of said compartments and a mud-ring at the lower ends of said compartments. 130
70. 14. In a boiler fire-box the combination of sides, each comprising an inner and outer flanged sectional shell, the flanges of said shells being secured together to form communicating compartments, heads closing the upper ends of the latter, a mud-ring closing the lower ends of said compartments and a plurality of drums constituting the top of the fire-box some of said drums being connected to and having communication with said compartments. 135
75. 15. In a fire-box the combination of a wall comprising flanged sections, a mud-ring, and a connecting plate from said flanged sections to said mud-ring, said connecting plate crossing the lower ends of the former and overlapping the latter and secured to both. 140
80. 16. In a fire-box the combination of a wall comprising sectional compartments, 145

a mud-ring, and a connecting plate from said compartments to said ring, said connecting plate crossing the lower ends of the former and overlapping the latter and secured to both.

17. In a fire-box the combination of a wall comprising compartments, a mud-ring, and a connecting plate from said compartments to said ring, said connecting plate crossing the lower ends of the former and overlapping the latter and secured to both.

18. In a boiler fire-box the combination of a plurality of drums forming the top of the fire-box with side walls, each comprising a plurality of sections some of which are secured to said drums and closing cups secured to the tops of said sections.

19. In a boiler fire-box the combination of a plurality of drums forming the top of the fire-box with side walls, each comprising a plurality of sections some of which are secured to said drums, the walls of said sections being deformed to coöperate with and for attachment of said sections to said drums and closing cups secured to the top of said walls.

In testimony whereof, I have signed my name to this specification, in the presence of two subscribing witnesses.

JAMES M. McCLELLON.
